UNITED STATES PATENT OFFICE

BECHER B. BOLTON, OF GLENDALE, CALIFORNIA, ASSIGNOR TO WILLA STEEN, OF BREA, CALIFORNIA

DESIGN FOR A TILE BLOCK

Application filed October 9, 1930. Serial No. 37,194. Term of patent 14 years.

To all whom it may concern:

Be it known that I, BECHER B. BOLTON, a citizen of the United States, residing at Glendale, in the county of Los Angeles and State of California, have invented a new, original, and ornamental Design for a Tile Block, of which the following is a specification, reference being had to the accompanying drawings, forming part thereof,

Fig. 1 is a plan of the tile block.

Fig. 2 is a side elevation looking in the direction of the arrow 2 indicated in Fig. 1.

Fig. 3 is an end elevation looking in the direction of the arrow 3 indicated in Fig. 1.

I claim:

The ornamental design for a tile block, as shown.

BECHER B. BOLTON.
